UNITED STATES PATENT OFFICE.

JAMES M. GEARING, OF PITTSBURGH, PENNSYLVANIA.

VALVE-MOTION FOR INTERNAL-COMBUSTION ENGINES.

1,287,289.

Specification of Letters Patent. Patented Dec. 10, 1918.

Application filed May 2, 1918. Serial No. 232,143.

To all whom it may concern:

Be it known that I, JAMES M. GEARING, of Pittsburgh, Allegheny county, Pennsylvania, have invented a new and useful Improvement in Valve-Motions for Internal-Combustion Engines, of which the following is a full, clear, and exact description, reference being had to the accompanying drawings, forming part of this specification, 10 in which:

Figure 1 is a central sectional view of an internal combustion engine embodying my invention;

Figs. 2, 3, 4, and 5 are diagrams showing 15 the moving parts in different positions; and

Fig. 6 is a detail view partly in section and partly in elevation of certain of the parts.

My invention has relation to improvements in valve motions for internal combustion engines, and particularly to engines of the four-cycle type employing a single sleeve valve which controls both the inlet and exhaust ports. The object of my invention is 20 to provide actuating mechanism for a valve sleeve of this character which will be simple and positive in its action and which will insure the correct movement of the valve sleeve at all times.

30 The nature of my invention will be best understood by reference to the accompanying drawings, in which I have shown the preferred embodiments thereof and which will now be described, it being premised, 35 however, that various changes can be made in the details of construction and arrangement of the several parts, without departing from the spirit and scope of my invention as defined in the appended claims.

40 In these drawings, the numeral 2 designates the engine cylinder having the head 3, junk ring 4, piston 5, connecting rod 6, crank 7 and crank shaft 8. 9 designates the exhaust ports, which are preferably provided in duplicate on opposite sides of the cylinder, and 10 designates the similarly arranged intake ports. 11 is the manifold for the intake and exhaust ports. These ports may be of any usual or suitable arrangement.

50 The numeral 12 designates the internal sleeve valve which forms a lining for the cylinder and which is provided with a single port 13, adapted to act alternately as an intake and exhaust port by being brought into

alignment, respectively, at the proper times with the ports 9 and 10. The upper end portion of this valve sleeve is shown as sealed by means of suitable packing 14, in the head 3, and another packing in the junk ring 4.

The numeral 16 designates an eccentric which is placed on the crank shaft 8, and whose strap 17 is connected to a toggle formed by the two link members 18 and 19. 65 The link 18 is connected at its opposite end to a fixed pivot pin 20, mounted on the frame of the engine. The opposite end of the link 19 is connected to a toggle formed by the two link members 21 and 22. The 70 link member 21 is pivotally connected at its opposite end at 23 to one side of the valve sleeve 12, and the opposite end of the link member 22 constitutes the strap of an eccentric 24, mounted on a half-speed shaft 75 25. This shaft is geared to run at half speed by any usual or suitable arrangement, and is made to rotate in the same direction as the crank shaft. The two members 21 and 22 are in the plane of the connecting rod center, as best shown in Fig. 6, while the members 17, 18 and 19 are at one side of such center so as to clear the connecting rod 6.

80 The eccentric 24 has a greater throw than 85 the eccentric 16, its throw being shown as approximately twice that of the eccentric 16. The two eccentrics are set at different angles, the eccentric 24 being shown as approximately 30° in advance of the eccentric 16. The eccentric 16 is set at an angle of 90° to the crank 7.

95 It will be seen that the strap of the eccentric 16 is connected to a toggle, one member of which is connected to the fixed point 20, while its other member is connected to the joint of another toggle formed by the members 21 and 22. It will be apparent, therefore, that the two eccentrics will exert a combined reciprocating action on the valve sleeve, the major part of the movement of the valve sleeve being imparted by the eccentric 24, and that each eccentric will modify and control the action of the other one, the entire movement being further controlled and guided by the fixed point 20, which, through the medium of the member 18, acts as a fixed heel or fulcrum. At times, the two eccentrics will co-operate to produce a relatively quick movement of the 100 105 110

valve sleeve, while at other times their action will be of a mutually opposing character tending to retard movement of said sleeve or to hold the sleeve stationary.

5 In Fig. 1, the parts are shown approximately in the position which they occupy at the middle of the exhaust stroke, the inlet ports being closed and the exhaust ports wide open. In these positions, it will be 10 noted that the eccentric 8 has just passed its outer high point, with the eccentric 24 approximately 30° in advance, and that the two eccentrics are approaching a position in which they will coöperate to act upon the 15 valve sleeve to quickly shift it to close the exhaust port and open the inlet port. In this figure, the valve sleeve is shown at the limit of its extreme outward movement.

In Fig. 2, the parts are shown in the positions which they occupy when the crank 20 shaft is rotated 120° from the position shown in Fig. 1, and the piston is starting its intake stroke. Both eccentrics are now coöperating to move the valve sleeve inwardly to fully open the intake ports.

In the position shown in Fig. 3, the crank 30 shaft has made a complete revolution from the position shown in Fig. 1, and the piston is in the middle of its compression stroke. All ports are now closed. It will be seen 35 that the two eccentrics are now in position to oppose each other and to hold the valve in this port-closing position during the compression and explosion strokes.

35 In Fig. 4, the parts are shown in approximately their position at the end of the compression stroke.

In Fig. 5, the parts are shown in approximately their positions at the end of the 40 explosion stroke, the exhaust ports now being open and the eccentrics being in a position to maintain these ports open during the exhaust stroke, as shown in Fig. 1.

The advantages of my invention will be 45 apparent, since it provides a simple, positive and reliable mechanism which will enable the use of a single sleeve valve for controlling all ports. It will be readily seen that the throw and setting of the eccentrics with 50 respect to each other and also their setting with respect to the crank angle may be varied to modify the movement of the valve sleeve

as may be necessary in any particular case or to meet different locations of and distances between port centers. The stroke of the 55 valve may also be varied by adjusting the fixed point 20, the higher this point, the greater being the stroke of the valve.

I claim:

1. In an internal combustion engine, valve-actuating mechanism comprising a valve member to be actuated, a half-speed shaft, an eccentric on said shaft, a toggle connecting said eccentric with the valve member, a crank shaft, another eccentric on the crank 65 shaft, and a second toggle to which the strap of the last named eccentric is connected, one member of the last named toggle being connected to the joint of the first named toggle and its other member being connected to a 70 fixed fulcrum point, substantially as described.

2. In an internal combustion engine, valve-actuating mechanism comprising a valve member to be actuated, a half-speed shaft, 75 an eccentric on said shaft, a toggle connecting said eccentric with the valve member, a crank shaft, another eccentric on the crank shaft, and a second toggle to which the strap of the last named eccentric is connected, one 80 member of the last named toggle being connected to the point of the first named toggle and its other member being connected to a fixed fulcrum point, the two eccentrics being set at different angles and having different 85 throws, substantially as described.

3. In an internal combustion engine, valve-actuating mechanism comprising a valve member to be actuated, a half-speed shaft, 90 an eccentric on said shaft, a toggle connecting said eccentric with the valve member, a crank shaft, another eccentric on the crank shaft, and a second toggle to which the strap of the last named eccentric is connected, one member of the last named toggle being connected to the point of the first named toggle 95 and its other member being connected to a fixed fulcrum point, the two eccentrics being set at different angles and at oblique angles with respect to the center line of the crank, 100 substantially as described.

In testimony whereof, I have hereunto set my hand.

JAMES M. GEARING.
